UNITED STATES PATENT OFFICE.

HENRY E. CURTIS, OF SAN JOSE, CALIFORNIA.

CARBURETER.

1,309,719.

Specification of Letters Patent. Patented July 15, 1919.

Application filed April 18, 1917. Serial No. 162,911.

To all whom it may concern:

Be it known that I, HENRY E. CURTIS, a citizen of the United States, and resident of San Jose, in the county of Santa Clara and 5 State of California, have invented a certain new and useful Improvement in Carbureters, of which the following is a specification.

My invention relates to carbureters, and the object of my invention is to provide a carbureter of simple construction that can 10 be easily and cheaply manufactured; that is adapted to supply the proper mixture of air and fuel under any and all engine loads and speeds; that will supply a small quantity of 15 a uniformly rich mixture for operating the engine at exceedingly low speeds; that will successfully and efficiently carburet the air with fuels of varying density; that will supply an initial charge of rich mixture to the 20 engine when the same is turned over slowly and thereby permit the quick and easy starting of the engine.

A device whereby the above and other objects are attained is illustrated, by way of 25 example, in the accompanying drawing and hereinafter described in detail.

In the drawing:—

Figure 1 is a longitudinal, sectional view through my improved carbureter.

30 Fig. 2 is a sectional view on line A—A of Fig. 1 with a choke valve inserted.

Fig. 3 is an end view of the carbureter taken on line C—C of Fig. 2.

Fig. 4 is an elevation of the throttle.

35 Fig. 5 is a detail sectional view on line B—B of Fig. 2.

Similar characters of reference refer to similar parts throughout the several views.

At 1 is indicated the hollow cylindrical 40 casing of the carbureter provided with air inlet 2 controlled at starting by choke valve 3, and discharge outlet 4 controlled by throttle 5. Cast integrally with body 1 is threaded flange 6 to which is screwed bowl 7 thereby 45 forming float chamber 8 in which is shown float 9 and fuel 10. Since any well known method of supplying fuel 10 and keeping the same at a constant level in chamber 8 may be used, I do not show or describe devices for this 50 purpose. At 11 is shown a Venturi tube having its inner surface in the form of a

short truncated cone 12 and a long truncated cone 13 joined by a short throat-portion 14, surface 12 being directed toward inlet 2. The outer surface of tube 11 is provided with a flange 15 fitting closely in body 1 and concentric with throat-portion 14, the proportions of this flange preferably being such that its thickness longitudinally of the tube is in excess of its width. The inner end of tube 11 is provided with an annular surface 16 adapted to fit closely in body 1 as shown, the space between flange 15 and the inner edge of surface 16 forming an expansion chamber 17.

A fuel nozzle is shown at 18 fitted in casing and secured in any appropriate way 1 at 19 and passing through bore 20 in tube 11 and having its discharge end positioned in substantially the center of throat-portion 14. The conduit 21 in nozzle 18 communicates, in this case, directly with the fuel 10 in chamber 8. At 22 are provided a plurality of orifices connecting chamber 17 with the interior of tube 11. The various elements above described are all positioned in fixed relation to each other.

An angularly projecting portion 23 is formed as shown on the side of casing 1 and the top of flange 6, and has a conduit 24 bored lengthwise therethrough to communicate with discharge outlet 4 at a point adjacent throttle 5 so as to operate in conjunction therewith when said throttle is closed or nearly closed, throttle 5 having a small opening formed therein as at 25 and substantially in alignment with said conduit 24 when said throttle is closed. The outer end of conduit 24 is threaded to engage a threaded adjusting screw 26. At 27 is shown a second conduit bored vertically through portion 23 and communicating with conduit 24 and having a pipe 28 fixed in communication with its lower end, said pipe passing inwardly and downwardly so as to have permanent communication with fuel 10 in chamber 8 as shown. Expansion chamber 17 and air inlet 2 are connected by a plurality of orifices 29 formed in flange 15. At 30 is shown the carbureting chamber and 10 at 31 is indicated the mixing chamber.

The parts indicated by numerals 23 to 28

inclusive form an auxiliary carbureting device which is extremely effective in starting the engine and in operating the same at very low speeds. When the engine is turned over at starting, the throttle 5 and choke-valve 3 being closed or nearly closed, the suction through opening 25 draws a small amount of air through tube 11 and a small but proportionally large amount of fuel from chamber 8 through conduits 27 and 24 respectively. This rich mixture gives almost instant results. When the engine is started choke-valve 3 is opened wide and throttle 5 is opened a distance, the increased load or speed now drawing the air through orifices 22 and throat portion 14 and fuel from the nozzle 18 as well as a small amount of fuel from conduit 24. The flow of fuel from conduit 27 into conduit 24 is regulated by adjusting screw 26. By the proper setting of screw 26 and throttle 5, I have found that I can run a machine equipped with this device steadily and smoothly as slowly as three miles an hour. As throttle 5 is opened for greater speeds and loads this auxiliary carbureting device is rendered inactive because of the reduced velocity of the mixture passing the discharge end of conduit 24. When the throttle 5 is opened wider as above set forth the action is as follows. The flow of air through throat-portion 14 draws fuel from nozzle 18 in the usual manner. The compensating air, however, is retarded in its passage through conduits 29 and orifices 22 on account of the large amount of surface with which it comes in contact. In passing through conduits 29 the velocity of the air is increased. As said air enters chamber 17 it immediately expands with the result that its velocity is reduced and its forward motion checked. This process is repeated as the air passes through orifices 22 into the interior of tube 11. One result of this action is that when throttle 5 is opened sufficiently wide to permit fuel and air to be drawn through tube 11, a large number of small jets of compensating air are injected into the mixture thereby assisting materially in the vaporizing process, and carrying condensation back into the mixture. The orifices 22 perform these functions best when formed as shown and directed inwardly and forwardly toward the throttle 5 as the injected air then more readily moves forward with the mixture and does not tend to form a blanket over the throat-portion 14.

It is manifest that if compensating air were allowed to flow into chamber 31 freely the suction through throat-portion 14 would be reduced correspondingly and insufficient fuel to secure a proper mixture would be drawn from nozzle 18. If flange 15 were omitted or made as thin as the wall or casting 1 there would be so little retarding of the air current as to be almost negligible, the

retarding being effected entirely by orifices 22. I have found this retarding to be insufficient, but have discovered that if conduits 29 are lengthened somewhat the air is retarded in its passage therethrough and substantially checked in its movement when it expands in chamber 17, and its forward movement is again retarded as it is drawn through orifices 22. By properly proportioning the number and size of conduits 29 to chamber 17 and orifices 22 I have discovered that the flow of compensating air into chamber 31 may be properly proportioned at all times to the flow of fuel and air from carbureting chamber 30. 80

While some carbureters use spring controlled devices for governing the flow of fuel from the nozzle, and others use reciprocating tubes operated automatically by the varying fluid pressures in the carburetor for governing the flow of fuel from the nozzle, I utilize, in the present invention, the frictional resistance offered by a number of openings of proper size and the choking effect of an expansion chamber, for securing the desired result. The word "unbroken" in the claims is used to designate an inclosing wall having no perforations or valve openings of any kind. 90

While I have shown and described one specific form of my invention, it is understood that changes in form, proportions, construction and operation may be made within the scope of the appended claims. 95

I claim:—

1. A carbureter comprising a cylinder having a valve controlled mixture outlet at one end thereof and an air inlet at the other end thereof, a Venturi tube fixedly positioned therein intermediate said inlet and said outlet and provided with outwardly extending and spaced portions to engage said cylinder and form therewith an expansion chamber having an unbroken outer wall, one of said outwardly extending portions having a thickness greater than its width and provided with conduits forming open but restricted communication between said expansion chamber and said air inlet, and said tube having a plurality of orifices formed therein connecting said expansion chamber with the interior thereof, and a fuel nozzle discharging into said tube and connected to a fuel supply. 110

2. A carbureter comprising a cylinder having a valve controlled mixture outlet at one end thereof and an air inlet at the other end thereof, a Venturi tube fixedly positioned therein intermediate said inlet and said outlet and provided with outwardly extending and spaced portions to engage said cylinder and form therewith an expansion chamber having an unbroken outer wall, one of said outwardly extending portions having a plurality of conduits formed therein to 115

100

125

130

provide open but restricted communication between said expansion chamber and said air inlet, and said tube having a plurality of orifices formed therein to connect said expansion chamber with the interior thereof, said orifices being greater in number and

smaller in cross-sectional area than said con-

duits, and a fuel nozzle discharging into said tube and connected to a fuel supply.

In testimony whereof I have hereunto affixed my signature this 11th day of April, 1917.

HENRY E. CURTIS.
